UNITED STATES PATENT OFFICE

125,090

DESIGN FOR A SHOE

Frank R. Merritt, Haverhill, Mass., assignor to
United Shoe Machinery Corporation, Flemington, N. J., a corporation of New Jersey

Application August 23, 1940, Serial No. 94,590

Term of patent 14 years

To all whom it may concern:

Be it known that I, Frank R. Merritt, a citizen of the United States, residing at Haverhill, in the county of Essex and Commonwealth of Massachusetts, have invented a new, original, and ornamental Design for Shoes, of which the following is a specification, reference being had to the accompanying drawing, forming part thereof.

In the drawing—

Fig. 1 is a perspective view of one side of a shoe showing my new design;

Fig. 2 is a plan view of the shoe;

Fig. 3 is a side elevation of the shoe showing the side opposite to that shown in Fig. 1; and

Fig. 4 is a cross sectional view taken along the line IV—IV of Fig. 2 and showing the appearance of the moccasin-type seam.

The dominant feature of my new design is the continuous moccasin-type seam which extends upwardly from the sole of the shoe at one side of the shank rearwardly of the center thereof, forwardly around the toe end of the shoe, and thence rearwardly and downwardly to a corresponding point on the sole at the opposite side of the shank of the shoe.

I claim:

The ornamental design for a shoe, substantially as shown and described.

FRANK R. MERRITT.
